UNITED STATES PATENT OFFICE.

ERNST LINDNER, OF NEW YORK, N. Y.

DESIGN FOR A GAS-BURNER FIXTURE.

SPECIFICATION forming part of Design No. 27,652, dated September 21, 1897.

Application filed April 29, 1897. Serial No. 634,475. Term of patent 7 years.

To all whom it may concern:

Be it known that I, ERNST LINDNER, a citizen of the United States, residing at New York, in the county and State of New York, 5 have invented and produced a new and original Design for an Incandescent-Gas-Burner Fixture, of which the following is a specification, reference being had to the accompanying drawing, forming a part thereof.

10 The annexed drawing shows a view in elevation of an incandescent-gas-burner fixture embodying my design.

The object of my invention is to produce a new and original design for an incandescent-gas-burner fixture; and the invention 15 consists in the configuration or shape of the burner-fixture, substantially as illustrated in the drawing.

The design for the burner-fixture comprises 20 the globe-shaped portion or chamber A, which is the particular characteristic of the design, the bottom cylindrical extension B, ornamented by a rope-like ring b, and the neck-

like top extension C, surmounted by the disk-shaped portion D, which is provided with a 25 series of vertical pieces d of ornamental configuration.

The globe-shaped portion A is provided circumferentially with the rope-like ring a, above which the surface of the globe is 30 formed with embossed tear-like ornamentations and below with a series of openings which are narrower at the bottom than at the top.

The distinctive feature of the design is the 35 ornamental globe-like portion or chamber A.

I claim—

The design for an incandescent-gas-burner 40 fixture, substantially as shown.

Signed at New York, N. Y., the 28th day 40 of April, 1897.

ERNST LINDNER.
